United States Patent Office.

L. D. COWLES, OF ROME O, MICHIGAN.

Letters Patent No. 80,605, dated August 4, 1868.

IMPROVED BUCKLE.

The Schedule referred to in these Letters Patent and making part of the same.

TO ALL WHOM IT MAY CONCERN:

Be it known that I, L. D. Cowles, of Romeo, in the county of Macomb, and in the State of Michigan, have invented certain new and useful Improvements in Buckles; and do hereby declare that the following is a full, clear, and exact description thereof, reference being had to the accompanying drawings, and to the letters of reference marked thereon.

The nature of my invention consists in the construction of a simple and cheap, and at the same time substantial buckle, adapted to almost any purpose where a buckle is wanted, and in the manner by which the same closes and takes hold of the strap.

In order to enable others skilled in the art to make and use my invention, I will now proceed to describe its construction and operation, referring to the annexed drawings, which form a part of this specification, and in which—

Figure 1 is a plan view,

Figure 2 a side view, and

Figure 3 a plan view of the inside frame.

A represents an oblong metal frame, the longer sides of which are bent or rounded, so that the end-plates or bars are higher than the centre of the frame. Near one end of this frame is a cross-bar, on which a strap is fastened.

Another frame, B, is made of similar shape to the frame A, but of such size as to work inside of it.

This frame is provided with one or more cross-bars *a a* in its centre, and a lug, C, on each side, projecting therefrom, which lugs rest on the upper edge of the side-bars on the frame A.

After the frame B is placed inside of the frame A, the strap is put in under the end-bars of the two frames, over the cross-bars *a a*, and under the other end-bars of said frames. By then pulling on this strap, and on the one fastened to the frame A, this frame will slide under the lugs C C until the end-bar of the same closes tightly on the strap, and holds it firmly at the centre of the buckle.

The frames A and B may be made of any suitable form or shape desired.

Having thus fully described my invention, what I claim as new, and desire to secure by Letters Patent, is—

The lugs C C, on the sides of the frame B, in combination with the frame A, having inclined edges, whereby the end-bars of the two frames are made to hold the strap, substantially as and for the purposes herein set forth.

In testimony that I claim the foregoing, I have hereunto set my hand, this 18th day of June, 1868.

Witnesses:
